UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

EXCAVATOR.

1,037,429.

Specification of Letters Patent.

Patented Sept. 3, 1912.

Application filed September 28, 1908. Serial No. 455,022.

To all whom it may concern:

Be it known that I, MORTON G. BUNNELL, a citizen of the United States of America, and resident of Chicago, Cook county, Illinois, have invented a certain new and useful Improvement in Excavators, of which the following is a specification.

My invention relates to excavators of the general type in which a drag-line bucket is employed as the means for tearing up the ground and transferring the dirt thus loosened from one place to another.

It relates more particularly to drag-line buckets of the kind disclosed in my prior application Serial Number 451,296, filed September 2, 1908, and is in the nature of an improvement thereon. In my said other application the bucket is so constructed that the load is automatically dumped from the rear end thereof by the final upward pull of the hoist-line.

My present invention, as will hereinafter more fully appear, consists in adapting the bucket to dump from its mouth or forward end. With this method the bucket is simple in form and no door or movable rear end wall is necessary for discharging the load, as in said prior application. Consequently the bucket is less liable to get out of order, and is more reliable in use.

In the accompanying drawings:—Figure 1 is a side elevation of an excavator provided with a drag-line bucket embodying the principles of my invention. Fig. 2 is an enlarged side elevation of the bucket shown in Fig. 1. Fig. 3 is a front elevation of the bucket shown in Fig. 2. Fig. 4 is an enlarged detail sectional view of the yielding or spring-locked shoulder against which the bucket is hoisted to dump the load therefrom. Fig. 5 is a plan of the bucket shown in Fig. 3. Fig. 6 is a view similar to Fig. 2, but showing the bucket in the act of dumping the load therefrom, being partially tilted or turned about its axis, the full range of movement being sufficient to bring the mouth of the bucket below and into position to freely discharge the contents thereof.

As thus illustrated, the excavator comprises a body A mounted on trucks or devices B for enabling the machine to move along. At its forward end the body of the machine is provided with a turn table or reversing circle C upon which is mounted the mast D. This mast, it will be seen, has its

upper end swiveled to a rigid upright frame E that is mounted on the platform or body portion of the machine. To the base or lower end of said mast a swinging boom F is secured in such manner that it can be adjusted up and down, so as to vary the height to which the bucket is elevated for dumping. At its outer end the said boom is equipped with a sheave f, and the mast has a similar sheave d at its upper end; and around these sheaves is arranged a raising and lowering rope or cable G which has one end secured at g to the block of the sheave f and the other end brought down and wound upon the drum or cylinder of a hand winch H, which latter is mounted on the mast. The said boom is provided with another sheave f' at its outer end and the mast is provided at its base with a sheave d'; and upon these two sheaves is supported the hoist-line I which carries the bucket J. The said hoist-line extends downwardly and around a sheave i mounted on the body of the machine, and thence back to one of the drums K which are mounted at the rear of the machine and driven by the engine k. The usual drag-line L is suitably secured to the bucket and then brought back into engagement with guiding sheaves carried by the forward structure of the body A, and thence rearward to one of the drums K, as illustrated. Another rope or cable M is applied to the circumference of the turn table or reversing circle C, and is operated by another of the drums K, whereby the mast and the boom carrying the bucket can be swung from one side to the other, so as to discharge the load at either side of the machine. It will be understood that the said ropes or cables and the drums for operating them can be controlled in any suitable manner, whereby the operator will have full control of the operations of the bucket. The said bucket J is preferably formed with an open mouth or front end j, a closed rear end j', and an open top j". A bail j" has its lower ends pivoted at j' to the sides of the bucket, so that the axis about which the latter tilts is nearer its forward end than its rear end. A chain or other flexible connection j" connects the rear end of the bucket with the top or cross bar j" of the said bail, whereby the weight of the bucket tends to hold it in upright or loading position, as shown in Figs. 1 and 2. The lower edge of

the mouth of the bucket has a cutting edge 5 j^7 which enables the bucket to cut into the ground and more effectively gather a full load of dirt. The drag-line L is preferably secured by chains or other flexible connections j^8 to the side bars j^9 of the bucket, thus giving the desired pull or line of draft necessary for properly loading the bucket as it is dragged along the ground.

10 At its forward end the bucket has a bail-shaped member j^{10} , the lower ends of which latter are pivoted at j^{11} to the forward upper corners of the bucket, in the manner shown. To the middle of the upper cross bar j^{12} of this bail there is secured a bracket j^{13} upon which are mounted the guide rolls j^{14} , which latter engage the hoist-line. It will be seen that the said hoist-line is secured to the middle portion of the cross bar 15 j^8 of the lifting or carrying bail j^3 , and that it then extends upwardly in a straight line to the sheave on the end of the boom. In so doing it passes through the yielding or spring bucket stop device N that is pivotally 20 mounted on the end of the boom. Within this device N there is provided a hollow plunger or movable stop member n which is provided with a bore or longitudinal passage n' through which extends the said 25 hoist-line. This member n is provided with a shoulder n^2 , and the casing or body n^3 of the said device is made hollow and provided with a shoulder n^4 . Between these two shoulders there is interposed a coil spring 30 n^5 , and with this arrangement it will be seen that pressure on the lower end of the member n is yieldingly opposed by the said spring.

In operation the bucket is lowered to the 40 ground by paying out the hoist-line, and the same is then filled by winding in on the drag-line. When the bucket is loaded, the drag-line is slackened off and paid out and the hoist-line is wound in so that the bucket 45 is raised to the desired height or level. When the bucket is brought to the position desired for dumping, a slight upward pull on the hoist-line I then causes the bracket j^{13} to engage the lower end of the stop member n , the contact being cushioned by the spring n^5 , thus avoiding shock or breakage. The continued pull on the hoist-line causes the bucket to rise, but inasmuch as the bail-shaped member j^{10} has at such time reached 55 the limit of its upward movement, it follows that the forward end of the bucket will be depressed, in the manner shown in Fig. 6. The construction is preferably such that this action can continue until the bucket is completely upset and its rear end brought above and its mouth below, the width of the bails j^8 and j^{10} being sufficient to permit this tilting or oscillating motion of the bucket. When this is done, the load is discharged by 65 gravity from the bucket, and as soon as the

hoist-line is slackened off the bucket begins to assume its normal or horizontal position, by reason of the fact that its rear end is heavier than its forward end, so that it assumes the position shown in Fig. 2, in which condition it is in shape to again be dragged along the ground for the purpose of getting another load. This operation is repeated until the desired extent of excavation is accomplished.

70 Thus it will be seen that I provide a hoist-line which has a straight or direct connection to the top of the bucket—that is to say, which extends in a straight line from the boom to the bucket, which hoist-line is available as a means for automatically dumping the load from the mouth or front end of the bucket. In other words, the final pull on the hoist-line is sufficient to automatically dump the load from the mouth or 80 open forward end of the bucket. In this way no doors or movable walls are necessary for the bucket. Such mouth also obviates the necessity of using latches or locks or tripping devices for releasing the bucket 85 when it is desired to dump the load. With my improved arrangement the weight of the load is sufficient to maintain the load in carrying position, and the dumping is accomplished by simply depressing the forward 90 end of the bucket by the final pull on the hoist-line.

95 As a matter of further and special improvement, the chain j^5 has an adjustable connection with the bucket, and is preferably a little longer than is necessary to hold the bucket in a horizontal position, as shown in the drawings. With this arrangement the point of attachment of the bucket to the chain can be varied along the length of the latter, so as to hold the bucket in different 100 positions, depending upon the character of the work. For clay and other kinds of soil, the bucket can be raised in a substantially horizontal position, in the manner shown. When working in sand, however, or loose gravel or other similar soil, it is then found preferable to lower the rear end of the bucket, so that it may be hoisted in a tilted or inclined position, the angle being sufficient to prevent the sand or gravel from spilling out of the mouth of the bucket. Thus the angle of the bucket can be varied 105 to suit different requirements.

110 What I claim as my invention is:—

1. An excavator comprising a drag-line bucket provided with a drag line operated by a drum, a hoist-line, the bucket being left free to tilt while rising, and means operated by the final upward movement of said hoist-line, carried on the bucket, for depressing the mouth of the bucket to dump the load therefrom.

115 2. An excavator comprising a drag-line bucket provided with a hoist-line, an ele- 130

- ment pivoted on the front of the bucket and serving, by the final upward movement of the hoist-line, to depress the mouth of the same to dump the load therefrom. 65
5. An excavator comprising a drag-line bucket provided with a hoist-line, an element pivoted on the front of said bucket and engaging said line, a stop for engaging the upper end of said element to depress the 10 mouth of the bucket, and means for operating said line to hoist the bucket and cause the said element to engage said stop. 70
4. An excavator comprising a drag-line bucket provided with a hoist-line, a yielding 15 or spring bucket stop at a point in the length of the line, and means on the bucket for engaging said stop to tilt the bucket and dump the load therefrom. 75
5. An excavator comprising a drag-line bucket provided with a drag line operated 20 by a drum, a hoist-line having a straight connection thereto, the bucket being left free to tilt while rising, and means operated by the final upward movement of the hoist- 25 line, carried on the bucket, for depressing the mouth of the bucket to dump the load therefrom. 80
6. An excavator comprising a drag-line bucket provided with a hoist-line, a lifting 30 or supporting bail for the bucket, to which the hoist-line is attached, a dumping bail pivoted on the front of the bucket, and means for engaging the upper end of the dumping bail for causing the same to depress 35 the mouth of the bucket to dump the load therefrom. 85
7. An excavator comprising a pivoted drag-line bucket, a flexible support for the rear end of said bucket, a hoist-line connected 40 with the pivots of the bucket, and with said flexible support, an element pivoted on the front of said bucket, and means for engaging the upper end of said element to depress the mouth of the bucket and 45 dump the load therefrom. 90
8. An excavator comprising a drag-line bucket provided with a drag line operated by a drum, a hoist-line extending straight downward thereto, the bucket being left 50 free to tilt while rising, and means located partly on the bucket and partly above the same, for depressing the mouth of the bucket to dump the load therefrom. 100
9. An excavator comprising a drag-line bucket provided with a hoist-line, means on the bucket operated by the final upward movement of said hoist-line, for depressing the mouth of the bucket to dump the load therefrom, and devices for varying the 55 angle of the bucket, disposed at the rear thereof, as set forth. 105
10. An excavator comprising a drag-line bucket provided with a hoist-line, an ele- 60
- ment pivoted on the bucket and serving by the final upward movement of the hoist-line to depress the mouth of the same to dump the load therefrom, and devices for varying the angle of the bucket. 110
11. An excavator comprising a drag-line bucket provided with a hoist-line, an element pivoted on the front of said bucket and engaging said line, a stop for engaging the upper end of said element to depress the mouth of the bucket, means for operating said line to hoist the bucket and cause the said element to engage said stop, and devices for varying the angle of the bucket. 115
12. An excavator comprising a drag-line bucket provided with a hoist-line, a yielding stop at the line, means on the bucket for engaging said stop to tilt the bucket and dump the load therefrom, and devices for varying the angle of the bucket. 120
13. An excavator comprising a drag-line bucket provided with a hoist-line having a straight connection thereto, means on the bucket operated by the final upward movement of the hoist-line, for depressing the mouth of the bucket to dump the load therefrom, and devices for supporting the rear of the bucket, and for varying the angle of the bucket. 125
14. An excavator comprising a drag-line bucket provided with a hoist-line, a lifting or supporting bail for the bucket, to which the hoist-line is attached, a dumping bail pivoted on the front of the bucket, means for engaging the upper end of the dumping bail for causing the same to depress the mouth of the bucket to dump the load therefrom, and devices for varying the angle of the bucket. 130
15. An excavator comprising a pivoted drag-line bucket, a flexible support for the rear end of said bucket, a hoist-line connected with the pivots of the bucket, and with said flexible support, an element pivoted on the front of said bucket, means for engaging the upper end of said element to depress the mouth of the bucket and dump the load therefrom, and devices for varying the angle of the bucket. 135
16. An excavator comprising a drag-line bucket provided with a hoist-line extending straight downward thereto, means for depressing the mouth of the bucket to dump the load therefrom, carried at the front of the bucket, and devices for varying the angle of the bucket, carried at the rear thereof. 140
